TELEPHONE AMPLIFIER

Albert Edward Judson, Coventry, England, assignor to
The General Electric Company Limited, London, Eng-
land

Filed Dec. 20, 1960, Ser. No. 63,283

Claims priority, application Great Britain Aug. 24, 1960

Term of patent 14 years

(Cl. D26—14)

Fig. 1

Fig. 2

Fig. 3

Fig. 4

FIG. 1 is a front perspective view of a telephone amplifier showing my new design;

FIG. 2 is a rear elevational view thereof;

FIG. 3 is a side elevational view thereof; and

FIG. 4 is a bottom plan view thereof.

The dominant features of my new design are shown in solid lines in the drawing.

I claim:

The ornamental design for a telephone amplifier, as shown and described.
